UNITED STATES PATENT OFFICE.

ZAIDA B. WEBB, OF WHIPPANY, NEW JERSEY, ASSIGNOR TO WEBB FOLDING BOX COMPANY, OF NEWARK, NEW JERSEY, A CORPORATION OF NEW JERSEY.

FOLDING BOX.

SPECIFICATION forming part of Letters Patent No. 690,496, dated January 7, 1902.

Application filed April 17, 1901. Serial No. 56,205. (No model.)

To all whom it may concern:

Be it known that I, ZAIDA B. WEBB, of Whippany, Morris county, New Jersey, have invented certain new and useful Improvements 5 in Folding Boxes, of which the following is a full, clear, and exact description.

My invention relates to improvements in folding boxes; and the object of my invention is to make a simple and cheap folding 10 box which can be set up without the use of glue, which can be easily manipulated, so as to set it up for use and fold it out flat, and which when in position for use has the parts interlocked and fastened in a way to make 15 the box exceptionally secure.

To these ends my invention consists of a folding box, the construction and arrangement of which will be hereinafter described and claimed.

Reference is to be had to the accompanying 20 drawings, forming part of this specification, in which similar figures of reference refer to similar parts throughout both views.

Figure 1 is a detail of the box-blank, and 25 Fig. 2 is a perspective view of the open box.

The box has a rectangular bottom portion 10, which is formed between the parallel side score-lines 11 and the end score-lines 12, and the side score-lines are prolonged, so as to 30 cross the side pieces 13, which project from opposite side edges of the box-bottom and separate the said side pieces from the flaps 14 14^a, which are formed on the ends of the side pieces and which when the side pieces 35 are turned up perpendicular to the box-bottom are adapted to fold inward, engage each other, and assist in forming the box ends. One of the side pieces has a finger-notch 13^a to facilitate grasping the top or cover when 40 the box is to be opened.

The flaps 14 14^a have notches 15 to enable them to be interlocked at the box ends, these notches being triangular incisions extending approximately half-way across the flaps, and 45 the notches in the flaps 14 are made in the upper or outer edge, while the notches in the flaps 14^a are made in the under or inner edge, and the flaps 14 are cut away slightly at the outer and upper corners, as shown at 16, so 50 that the two sets of flaps may be more readily placed in engagement. This scheme for

locking flaps together is not in itself new, and the opposed flaps are engaged by locking the notched part of one upon the notched part of the other, as shown clearly in Fig. 2. 55

Projecting from the end edges of the box-bottom 10 are the end pieces 17, which are adapted to be turned up in forming the box ends, and each end piece has at its free edge a flap 18, adapted to be turned up inwardly 60 into the box to protect the contents thereof, and the flap forms another purpose too—that of giving sufficient body to the box end to receive the parallel slots 20, which extend from the score-lines 12 outward in each box end. 65 The flaps 18 are separated from the end pieces 17 by the score-lines 19, although it will be understood that wherever score-lines are shown and referred to it is because they are used as a convenience and not as a necessity. 70

By having the end pieces 17 extended into the flaps 18, so that the slots 20 may be appropriately placed, sufficient stock is provided to prevent the slots from tearing out, and, furthermore, the slots being long, enables 75 them to readily receive the binding or locking flaps 14 14^a, as will be presently described.

The box has preferably a top or cover 21, of the kind usual to folding boxes, this being separated from the side pieces 13 by a score-line 22, and the cover or top, which is of the same size as the bottom 10, has a terminal flap 23, which is separated from the top or cover by a score-line 24 and is adapted when the box is closed to be tucked down between 80 the front side 13 of the box and the box contents, the flap being further bound by the protective flaps 18.

When the box is to be set up, the end pieces are turned up, with the flaps 18 sticking up 90 comparatively straight, and the side pieces 13 are also brought up to a perpendicular position, while the flaps 14 14^a are turned inward and their ends thrust through the slots 20 of the end pieces. As this is done the flaps 95 14 are brought underneath and the flaps 15 closed down upon them, so that the notched portions 15 of the two flaps at each end interlock, and thus the whole box is fastened firmly in place. This fastening is made still 100 more secure when the flaps 18 are tucked inward to cover the box-top, as this act abso-

lutely locks the flaps 14, so that they can be displaced only by being torn out. Thus when the cover 21 is closed down and the flap 23 tucked in a package is formed which is not 5 only very neat in appearance, but which is perfectly secure.

It will be seen from the foregoing description that the box is of great simplicity, that it can be set up almost instantly, and that the 10 box is well adapted for any of the uses to which such articles are put. It will be further observed that the parallel slots 20 make in the box end a strap or keeper which covers and binds the interlocked portions of the 15 flaps 14 14^a.

Having thus described my invention, what I claim as new, and desire to secure by Letters Patent, is—

As an improved article of manufacture, a 20 folding box comprising a bottom portion, end pieces projecting from two edges of the bot-

tom portion, said end pieces being provided with extension-flaps adapted to fold inward as usual, keepers or straps formed on the end pieces and flap by making slots, which slots 25 extend from the end pieces up into the extension-flaps, side pieces on the two remaining edges of the bottom, and end flaps projecting from the end portions of the side pieces, said flaps being notched and adapted 30 to be tucked through the slots in the end pieces and their extensions and engage with each other so that when engaged they will be bound in place by the aforesaid straps or keepers.

In testimony whereof I have signed my name to this specification in the presence of two subscribing witnesses.

ZAIDA B. WEBB.
